RING PACKING

Application filed August 30, 1927. Serial No. 216,351.

My invention relates to ring packing.

The principal object of my invention is to devise a ring packing for pistons, valves and other mechanical devices of a similar operative character which is designed to exert a uniform radial pressure against the wall of the cooperating cylinder or chamber, unaffected by the pressure of the surrounding working fluid.

10 A further object is to devise a packing of the character described in which the pressure exerted thereby is occasioned solely by its inherent, elastic nature, the construction of said packing rendering possible the maintenance of a constant pressure against the cooperating wall for some predetermined time, with successive renewals thereof during the life of the packing.

20 A further object is to devise a metallic packing of a double ring construction which effectively prevents leakage of the working fluid without undue wear of the coating wall, or of the packing itself, the useful life of the latter being accordingly increased beyond that now obtainable in the art.

25 In reciprocating engines, pumps and mechanisms of a similar character, the necessity of interposing a non-leakage construction between the piston and cylinder wall has resulted in a variety of proposed solutions. Chiefly, they comprise either a soft packing, such as hemp, which is suitably retained in position, or metallic rings, with or without springs, which when compressed by the cylinder wall are intended to exert a uniform, radial pressure thereagainst. The first type has been largely abandoned for prime movers, owing to the difficulty of repacking, considerable friction losses, and the use of high pressure steam. The metallic packing has achieved more success, particularly in the spring ring type but the latter is still characterized by several operating disadvantages in connection with steam and internal combustion engines.

30 The pressure which a spring ring exerts against a cylinder wall depends upon its size and details of construction and is greatest when first placed in position, the pressure thereafter decreasing with use. The

original pressure can only be approximately restored by "respringing" the ring, which tends to increase the leakage at the split portion. Again, since the standard form of ring is capable of lateral movement in its groove, the working fluid passes behind the ring through the split and serves to increase the pressure with which the ring acts against the cylinder wall, particularly on the side of the ring opposite the split, with consequent increase in wear of the several parts on one side. In horizontal engines of large size, the latter defect is further accentuated by the tendency of the ring to bear more heavily against the lower portion of the cylinder wall under the action of gravity. To a certain extent, the tendency to excess pressure on one side of the ring has been eliminated by using a double ring construction, the splits thereof being on opposite sides of the piston, thereby operating to equalize the wear on the cylinder wall. In the latter instance, however, the fluid pressure still occasions more wear of the cylinder wall and rings than is desirable.

35 The existence of the foregoing situation has resulted in the conception of the ring packing embodied in the present application. Briefly, it comprises a metallic ring which is retained in a wedged manner on the piston so that the pressure which it exerts against a cylinder wall is due solely to its inherent elasticity, positive means being utilized to prevent the working fluid acting for that purpose. Accordingly, friction with its accompanying wear is reduced to a minimum without affecting the non-leakage capacity of the packing. As wear occurs on the working face of the ring, relieving the side thereof will again cause the ring to bear against the cylinder wall, since the elasticity of the ring tends continually to expand it in a radial direction. Hence, since the packing operates only under a pressure which is sufficient to prevent leakage, it is superior as regards longevity to the ring of standard type.

40 Preferably, my improved packing is embodied in a double ring construction, because of its improved sealing capacity over

single rings of equal size. The same principle is applied, as regards the effect of the fluid pressure, to the elements comprising the ring as between themselves, as has been 5 discussed above for the ring as a unit; that is, the ring as an entity is not only locked in position, but the elements of the ring are interlocked with each other.

These and further objects of my invention 10 will be set forth in the following specification, reference being had to the accompanying drawing, and the novel means by which said objects are effectuated will be definitely pointed out in the claims.

15 In the drawing:

Fig. 1 is an elevation, partly in section, of a piston showing my improved ring packing applied thereto.

Fig. 2 is a view looking in the direction 20 of the arrow 2 in Fig. 1, showing a portion of the segmental retaining ring utilized for maintaining the packing in position.

Fig. 3 is a view of a portion of Fig. 2, looking in the direction of the arrow 3 in 25 said figure.

Fig. 4 is a view similar to a portion of Fig. 1, illustrating a modification of the ring packing.

As shown in the drawing, the numeral 10 30 represents a piston rod on which is secured in any approved manner a piston 11. In the lateral surface of said piston is recessed a circumferential groove 12 of convenient width and depth, the sides of said groove 35 being parallel to the diameter of said piston. A pair of packing rings 13 are seated against said walls in spaced relation, each of said rings comprising an element 14, L-shaped in section with the base thereof angularly 40 inclined to the diameter of said piston and facing towards the base of the ring on the opposite sides of the groove 12, and an element 15 which is seated within the element 14 and between the latter and the adjacent 45 wall of the groove 12. The peripheral surfaces of the elements 14 and 15 project beyond the lateral surface of the piston 15 when properly seated as hereinafter explained and are aligned to constitute the 50 working face of the packing.

The elements 14 and 15 may be split as at 16 and 17, respectively, in order to form a spring ring packing.

From the foregoing, it will be understood 55 that, as shown in Fig. 1, the underside of the upper packing and the upperside of the lower packing converge inwardly toward the vertical center line of the piston. In order to maintain said packing in position, a retaining ring composed of a plurality of segments 18 is employed, each segment being 60 fixed in position by screws such as 19 and having inclined upper and lower surfaces for cooperating with the similarly inclined 65 surfaces of the packing rings 13. The ends

of each segment may be notched as at 20 for engagement with the coacting ends of adjacent segments in order to obtain a satisfactory application of the retaining pressure 70 against the packing.

In placing my improved ring packing in position, the latter will be expanded radially as permitted by the splits 16 and 17 until the internal diameter thereof becomes sufficiently larger than the outside diameter of the piston to permit seating of the packing in the groove 12. The segments 18 will then be placed in position as noted above. The size of the packing 13 will depend upon the operating 75 conditions as regards the requirements of radial pressure and when initially seated, the relation between said packing and the segments 18 will be such as to secure an adequate projection of the working face of the 80 packing beyond the lateral surface of the piston when in position in the cylinder. The natural elasticity of the packing will exert the required radial pressure against the cylinder wall, but the wedged relation existing 85 between said packing and said segments will effectively prevent any radial movement outwardly of the packing due to the pressure of the working fluid. Excessive wear from the latter cause is accordingly prevented with 90 an increase in the life of the packing.

After the packing has worn sufficiently so 95 that it no longer bears with the proper pressure against the wall of the cylinder, it may be removed from the piston and the thickness thereof decreased by relieving in any suitable manner that face thereof which is seated against the wall of the groove 12. Accordingly, when again placed in said groove, 100 it will be apparent that the decreased thickness of the packing will permit a further 105 radial movement that will be adequate for the purpose of restoring a satisfactory non-leakage pressure against the cylinder wall.

In Fig. 4 is illustrated one modification of 110 the structure shown in Fig. 1. In the latter, the packing rings 13 are beveled on the inside, 115 relative to the segments 18, whereas in the modification, said rings are beveled on the outside. The same rings may be employed by merely reversing their position and inclining the opposite walls 21 of the circumferential groove 22 for coaction with similarly inclined surfaces of the packing rings 23. The walls 21 converge outwardly from the lateral surface of the piston 24 and, when 120 retained in position by a ring composed of segments 25, is effectively locked against radial movement. The manner of applying the packing 23 to the position, its style of functioning and use are similar to the packing 125 described above.

Either of my suggested modes of construction offers a very efficient means for satisfactorily controlling the outward thrust of the packing with manifest advantages from the 130

standpoint of wear, but without affecting in the slightest degree the primary function of the packing. It will be noted that the packing as a unit is not only locked against such movement, but in the event that a double ring construction is employed, the elements thereof are mutually interlocked against a similar action. However, it will be distinctly understood that the essence of my invention resides in the control of the outward, radial movement of the packing and that, accordingly, this function is not dependent upon the use of a series of packing rings for each piston, as shown in Fig. 1, nor upon the use of a double ring construction. Moreover, it will be apparent that the conception embodied in this application is not only adaptable to pistons, but also to piston valves and many other devices where similar operating conditions obtain.

While I have shown one set of elements and combinations thereof for effectuating my improved ring packing, it will be understood that the same is for the purpose of illustration only and in nowise to limit my device to the exact forms and structures shown, for many changes may be made therein without departing from the spirit of my invention.

I claim:

1. The combination with a member having a groove, of packing disposed in said groove comprising an inner and an outer ring arranged in nested relation, said inner ring being L-shaped in section with one limb thereof angularly inclined to the depth of said groove, said outer ring having a side similarly inclined for coaction with said limb for retention against radial movement by said inner ring, and a segmental, retaining ring including an inclined face for cooperating with said inner ring to limit the outward radial movement of the same, said ring being removable in segments from said member independently of said rings.

2. The combination with a member having a groove, of packing comprising a pair of rings disposed in said groove in spaced relation, each of said rings being composed of interlocking elements, and a segmental retaining ring for limiting the outward radial movement of said packing rings, said ring being removable in segments from said member independently of said rings.

3. The combination with a member having a groove, of packing comprising a pair of rings disposed in said groove in spaced relation, each of said rings being composed of interlocking elements arranged in nested relation, and a segmental retaining ring for limiting the outward radial movement of said packing rings, said ring being removable in segments from said member independently of said rings.

4. The combination with a member having a groove, of packing disposed in said groove

comprising an inner and an outer ring arranged in nested relation, said inner ring being L-shaped in section with one limb thereof angularly inclined to the depth of said groove, said outer ring having a side similarly inclined for coaction with said limb for retention against radial movement by said inner ring, and means cooperating with said nested rings and the groove for limiting the outward radial movement of said rings.

5. The combination with a movable member having a groove, of packing comprising a pair of rings disposed in said groove in spaced relation, each of said rings comprising an inner and an outer ring arranged in nested relation, said inner ring being L-shaped in section with one limb thereof angularly inclined to the depth of said groove, said outer ring having a side similarly inclined for coaction with said limb for retention against radial movement by said inner ring, and a retaining ring having inclined faces for cooperating with said inner rings for limiting the outward radial movement of said packing.

6. The combination with a movable member having a groove, of packing comprising a pair of rings disposed in said groove in spaced relation, each of said rings comprising an inner and an outer ring arranged in nested relation, said inner ring being L-shaped in section with one limb thereof angularly inclined to the depth of said groove, said outer ring having a side similarly inclined for coaction with said limb for retention against radial movement by said inner ring, and a retaining ring cooperating with said nested rings and the groove for limiting the outward radial movement of said packing.

In testimony whereof, I affix my signature.
JOSEPH F. BATTY.
